[57] CLAIM

The ornamental design for a terminal, substantially as shown and described.

DESCRIPTION

FIG. 1 is a perspective view of a terminal incorporating our new design;

FIG. 2 is a front elevational view thereof on an enlarged scale;

FIG. 3 is a top plan view thereof on an enlarged scale;

FIG. 4 is a left side elevational view thereof on an enlarged scale;

FIG. 5 is a right side elevational view thereof on an enlarged scale;

FIG. 6 is a rear elevational view thereof on an enlarged scale;

FIG. 7 is a bottom plan view thereof on an enlarged scale;

FIG. 8 is a top plan view of a second embodiment of our new design; and

FIG. 9 is a perspective view of the embodiment shown in FIG. 8.
